UNITED STATES PATENT OFFICE.

HARRY D. PHOENIX, OF SYRACUSE, NEW YORK.

DESIGN FOR A TELEPHONE WALL CABINET.

Application filed October 6, 1925. Serial No. 15,033. Term of patent 14 years.

To all whom it may concern:

Be it known that I, HARRY D. PHOENIX, a citizen of the United States, residing at 360 Midland Avenue, Syracuse, New York, have invented a new, original, and ornamental Design for Telephone Wall Cabinet, of which the following is a specification and description, reference being had to the accompanying drawing, forming part thereof. The figure is a perspective view of the telephone wall cabinet of my design.

I claim:

The ornamental design for a telephone wall cabinet as substantially shown.

H. D. PHOENIX.
